UNITED STATES PATENT OFFICE.

GEORGE L. DAVISON AND DAVID R. MATHIAS, OF CHICAGO, ILLINOIS,
ASSIGNORS TO PROTECTED FURNACE PORT CO., OF CHICAGO, ILLINOIS,
A CORPORATION OF ILLINOIS.

FURNACE-ARCH.

SPECIFICATION forming part of Letters Patent No. 783,778, dated February 28, 1905.

Application filed October 26, 1903. Serial No. 178,657.

To all whom it may concern:

Be it known that we, GEORGE L. DAVISON and DAVID R. MATHIAS, both residents of Chicago, in the county of Cook and State of Illinois, have invented certain new and useful Improvements in Furnace-Arches, of which the following is a specification.

This invention relates to improvements in furnace-arches, and refers more specifically to a water-cooled arch particularly adapted for use in conjunction with open-hearth furnaces.

The salient object of the invention is to provide a construction which will successfully withstand the intense heat of an open-hearth furnace and which is at the same time of simple and economical construction.

To this end the invention consists in the matters hereinafter described, and more particularly pointed out in the appended claims.

In the drawings, Figure 1 is a horizontal sectional view of an open-hearth furnace, taken on the indirect line 1 1 of Fig. 2 and looking downwardly. Fig. 2 is a longitudinal sectional view of the furnace, taken on line 2 2 of Fig. 1. Fig. 3 is a cross-sectional view taken on line 3 3 of Fig. 2 and looking in the direction of the arrows. Fig. 4 is another cross-sectional view taken on line 4 4 of Fig. 1 and looking in the direction of the arrows.

Referring to the drawings, 1 designates the main furnace-chamber, provided at each end with inlets, as 2 2, and also with a suitable runner 3, which communicates with the interior of the furnace through the bed thereof, as indicated at 4.

5 designates the upper wall or roof of the furnace-chamber, which is of refractory material and has the form of a relatively flat arch, the roof of the chamber being given this 40 form for the purpose of confining the combustion into close proximity with the upper surface of the material treated, but without bringing said upper wall into direct range of the inflowing burning gases.

45 The opposite ends of the furnace are similar in construction, and in use the direction of circulation of the gases of combustion through

the furnace is reversed at intervals, the inlet-duct of a given end becoming the outlet duct or flue, and vice versa.

With each duct or outer arch 2 is arranged to communicate separate air and gas passages 6 and 7, respectively, the passages 6 and 7 being arranged to converge and meet at a point within the respective arches 2 a short 55 distance outside of the main chamber, as shown clearly in Fig. 2. That portion of the partition-wall 8 which separates said passages which forms the point of conflux of the two passages constitutes an arch 9, which arch 60 forms the chief feature of the present invention. The supplies of gas and air admitted to the furnace through the passages 6 and 7 are highly heated and an intense combustion takes place, the combustion commencing at 65 the point where the two supplies meet and extending thence throughout the length of the furnace-chamber. It will be noted that the upper or air passage 6 is deflected downwardly at its point of conflux with the gas-passage, 70 and the inleading-duct 2 extends in continuation of the air-duct 6, so that the general direction of the inlet is obliquely downwardly toward the center of the furnace-chamber. It is important that the gases of combustion be 75 thus directed downwardly and inwardly in order that they may act more effectively upon the material being treated and also in order that the roof of the chamber may be protected. Heretofore the point of the arch 9 has 80 been rapidly burned away by the intense combustion in spite of the use of the most highly-refractory materials commercially available. As the point of the arch is burned back or shortened it will be obvious that the general 85 direction of the inflow becomes changed and approaches the horizontal and sometimes in extreme cases is so changed as to be directed upwardly against the roof of the furnace-chamber. The alternate reversal of the circulation through the furnace undoubtedly contributes to the rapid burning away of the points of the arches, as above described.

It is the object of the present invention to

provide an arch which will withstand the heat and will not be rapidly burned away, and to this end we provide an underlying support consisting of a series of water-tubes 10, arranged 5 side by side and supporting the refractory material constituting the arch proper. The several pipes 10 are connected at one end with a suitable supply-header 11, as best seen in Figs. 1 and 3, and at their opposite ends dis- 10 charge into an outlet-trough 12, the several pipes being arranged to extend entirely through the furnace from side to side and at their central portions bridging or overlying the lower or gas ducts 7. The header 11 com- 15 municates with any suitable source of water-supply, and in use sufficient water is circulated through the pipes to maintain the latter cooled below the softening-point, notwithstanding the intense heat to which they are 20 subjected.

It is to be noted that in the preferred construction shown the refractory material of the arch is all arranged above the supporting and protecting tubes 10, or, in other words, 25 the tubes are not embedded within and covered by the refractory material. With this construction the arch remains practically intact, notwithstanding the refractory portions thereof may be more or less fractured by the 30 intense heat, and the arch is not eaten away or shortened in use. This is a feature of great importance, since it is found in practice that as soon as the arch has been thus shortened to any considerable extent the direction of the blast changes and the roof-wall 35 of the furnace is rapidly destroyed. Another feature of advantage of our construction is that by using the water-tube supports for the refractory material refractory brick may be 40 used composed of material which are more highly refractory than silica brick, but more susceptible of fracturing and crumbling under intense heat—such, for example, as magnesite and chrome bricks.

45 Still another and very important feature of the present invention resides in the facility with which the arch may be repaired without interrupting the operation of the furnace. The refractory superstructure of the arch 50 will be burned off gradually, especially at its free or exposed edge; but as soon as it is to any substantial extent deformed it may be repaired by simply depositing a small quantity of suitable pulverized or granular refractory material, which will vitrify or burn 55 onto the upper edge of the arch. This material may be passed in through the side doors 13 of the furnace by means of a long-handled paddle or spoon-like tool. The arch may thus 60 be repaired from time to time without interrupting the operation of the furnace, and when it is considered that the preservation of the integrity of the inlet-passages means the preservation of the entire furnace indefinitely or at least for a greatly lengthened 65

period the importance of our invention is apparent.

While we have herein shown and described a preferred embodiment of our invention, yet it will be understood that the invention may 70 be otherwise embodied, and we do not, therefore, limit ourselves to the construction shown except to the extent that the same is made the subject of specific claims.

We claim as our invention—

1. In an open-hearth furnace, the combination with the main chamber, of upper and lower flues leading into one end thereof and a horizontally and transversely extending divisional arch separating said upper and lower 80 flues at or near their point of entrance to the main chamber, said divisional arch comprising an upper layer of refractory material and an underlying transversely-extending water-cooled structure, underlying and directly supporting substantially all parts of the refractory material of those portions of the divisional arch which form the point of conflux 85 of said upper and lower flues.

2. In an open-hearth furnace, the combination with the main chamber and main flue leading into one end thereof, and downwardly and inwardly inclined in its general direction, of gas and air passages converging and leading into said main flue and a divisional arch 95 at the point of conflux of said passages consisting of a series of underlying water-tubes, a superposed refractory brick structure, and means for circulating water through said tubes, substantially as described.

3. In an open-hearth furnace, the combination with the main chamber and main flues communicating with the respective ends of said main chamber, of air and gas passages leading into each of said main flues and arranged in superposed relation to each other, and divisional arches arranged at the respective points of conflux of the air and gas passages, each divisional arch being formed of an underlying horizontally-disposed, transversely-extending bridging series of closely-contiguous water-tubes, and a superposed refractory brick structure, as and for the purpose set forth.

4. In a device of the class described, the combination with the body of a furnace, and an outer arch at each end of the same, of an inner arch having a flat lower surface within each of said outer arches and out of contact therewith, passages for conducting gas to one side of said inner arch, and air to the other side thereof, and a plurality of water-pipes lying immediately below the said inner arch and in continuous contact with the lower surface thereof.

5. In a device of the class described, the combination with the body of the furnace and an outer arch at each end of the same, of an inner arch within each of said outer arches, and out of contact therewith, passages for conduct-

ing gas on one side of said inner arch and air on the other side thereof and means for artificially cooling said arches.

6. In a device of the class described, the combination with the body of the furnace and an outer arch at each end of the same, of an inner arch within each of said outer arches, and out of contact therewith, passages for conducting gas to one side of said inner arch and air to the other side thereof, and a series of water-pipes underneath each of said inner arches, said pipes serving the double purpose of cooling said arches and supporting loosened portions thereof.

15 7. In a device of the class described, the combination with the body of the furnace, of suitable gas and air ports arranged one above the other at each end of the furnace, said ports being adapted to serve at certain times as inlet-ports, and at other times as exhaust-ports, of a substantially horizontal septum separating said ports, and a series of closely-contiguous water-conducting pipes arranged in con-

tact with and below said septum, said pipes serving the double purpose of cooling the septum and supporting any loosened portions thereof.

8. In a device of the class described, the combination with the body of the furnace, of gas and air ports arranged one above the other at each end of the furnace, such ports serving at certain times as inlet-ports and at other times as exhaust-ports, a horizontal arch separating each pair of said ports, the edge of which is exposed freely to the interior of the furnace and a water-cooled shield below each of said arches at the edge nearest the center of the furnace, said shields extending across the entire width of said inner arches, and serving the double purpose of protecting the surface thereof from heat, and supporting the same.

GEORGE L. DAVISON.
DAVID R. MATHIAS.
